UNITED STATES PATENT OFFICE.

CHESTER H. BRASELTON, OF NEW YORK, N. Y.

LIQUID-SUPPLY SYSTEM.

Application filed June 6, 1922. Serial No. 566,380.

This invention relates to a system and mechanism for transporting fluid stored in a main and lower tank or reservoir to an auxiliary tank at a higher level from which subsequently fluid may be transmitted by gravity to a distributing device for use in some type of power plant, as, for example, an internal combustion engine of an automotive vehicle. Specifically, the invention relates to an auxiliary tank and pump combination, fuel distributing system in which the pumping action is induced by the movement of the support upon which the tank is mounted, this movement causing a reciprocating displacement of a weighted piston within the tank.

An important object of the invention is the provision of mechanism associated with the pump whereby the pumping action is positively terminated when the supply of liquid within the tank has reached a predetermined level, fixed by the capacity of the tank.

Another object associated with the above named object is the utilization of mechanism for slowing down or retarding the pumping action as the supply of liquid in the tank becomes relatively large. It is an object also to provide retarding or damping mechanism for the pump plunger which is ineffective unless submerged in the liquid which is being pumped in the tank, the retarding action of the enclosed air above the piston being negligible. Another important object is the provision of means for effectively sealing the cylinder piston connection thereby preventing the escape or entry of gases into the pump chamber and permitting it to operate at its highest efficiency.

It is an object also of the invention to provide a plunger or reciprocating element having a small pivotal action between the piston proper and the plunger and permitting a slight lateral movement of these parts thereby obviating strain upon the piston head and allowing free axial movement thereof within the pump cylinder. It has been found advisable also to prevent abnormal movement of the plunger, and it is an object, therefore, of the invention to provide means for limiting the axial movement of the plunger and accelerate the return of the plunger to its normal position.

Various other objects are also within the scope of this invention such as relate to various details of construction and manufacture and assembly as will become apparent from

a consideration of the illustrative embodiment of my invention shown in the accompanying drawing and described in detail hereinbelow.

Referring to the drawings,

Figure I is a conventional elevation of an automobile embodying my invention;

Figure II is an axial section of the tank pump element showing the various parts in detail;

Figure III is a plan view of the retarding valve taken on line III—III of Figure II;

Figure IV illustrates an element of the plunger taken on line IV—IV of Figure II;

Figure V and Figure VI show modified forms of plunger retarding valves.

The fuel supply of the automobile shown in Figure I is derived from the main tank or reservoir 1 situated in the rear of the automobile from which part it is conducted by means of a pipe 2 to the auxiliary tank 12, which is secured to the dash board 3.

From the tank 12 the liquid feeds by gravity through conduit 4 to the carbureter 5 whence it is distributed in the usual manner to the intake manifold of the internal combustion engine 6.

The tank 12 as illustrated clearly in Figure II is formed with an outer shell or casing 13 of cylindrical construction having in its top a stamping 14 apertured at its center to receive a tubing 15. A second stamping 16 at the base of the casing is apertured at the center to receive a pipe fitting 17 and at its side to receive the outlet coupling 18. A coupling 19 is screw-threaded on the fitting 17, such coupling forming a connection with the main tank pipe 2, while the coupling 18 is connected to the pipe 4 leading to the carbureter. The lower plate or stamping 16 is formed with an upturned flange 20 which is welded or soldered to the base of the casing 13. The upper or cover stamping 14 is, however, made detachable so that access can be had to the interior of the tank for the purpose of inspecting or replacing parts. To the upper edge of the cylinder 13, there is soldered a flanged ring 21 which is adapted to be detachably connected to a radial flange 22 extending from the top plate 14 by means of screws 23, there being a washer or gasket 24 of cork or other material placed in between the flanges so as to make the joint gasoline or liquid tight. The outer edges of both the ring 21 and flange 22 are downturned to form

contacting surfaces so as to prevent lateral movement of the top plate and, moreover, hold the gasket in position between the flanges.

5 The pump cylinder 25 is fixed to the interior of the fitting 17 and extends to approximately one-third of the height of the casing, although said dimension is purely arbitrary, it being permissible to vary the relative 10 length of the cylinder in accordance with the dimensions and weights of the other parts of the pump and casing. Fitting into the base of the cylinder is a bushing 26 having a radially extending outer flange 27 adapted to 15 rest beneath the lower end of the cylinder and upon an annular gasket 28, which gasket is adapted to prevent leakage between the fittings 17 and 19 and the cylinder 25. Beneath gasket 28 and directly above the inlet 20 opening is a mesh strainer 29 adapted to prevent foreign particles from entering the pump chamber 30.

In the base of the bushing 26 is formed a relatively constricted opening 31 extending 25 about one-third the axial length of the bushing. The central portion 32 of the inner part of the bushing is relatively enlarged forming a shoulder 33 between the constricted portion and the median portion, the upper 30 part 34 of the bushing being still further enlarged forming a second shoulder 35. Upon the shoulder 33 a valve plate 36 is adapted normally to rest. As illustrated, the valve consists of a thin plate stamping 35 of circular formation preferably resting upon the shoulder 33 and since the outer portion of the shoulder is channelled as at 37, sticking due to surface tension is reduced to a minimum. The movement upward of the 40 valve is limited by contact with the lower end of a tube 38 which extends upward into the interior of the pump chamber 30. This tube is held in position by means of an integral annular rib 40 which rests upon the shoulder of the bushing forming a tight fit 45 thereupon. It is thus apparent that both below and above the rib of the tubing there exists an annular spacing between the tube 38 and the bushing 26 on the one hand, and the tube and the interior of the cylinder 25 50 on the other hand, the space between the tubing and the bushing serving the same function as the annular channel 37 in preventing undue restriction on the action of the valve. The spacing above the rib 40 is 55 adapted to permit axial up and down or reciprocating movement of the extended wall 41 of the piston head 42, which, as will be seen because of the fact that a pocket is formed 60 in this annular channel above the shoulder, wherein liquid may accumulate, forms a seal of liquid between the moving end wall 41 of the piston and the inner wall of the cylinder 25 thereby preventing movement of 65 air into and out and thus increasing the ef-

ficiency of the pump to the highest point possible.

The piston head 42 is formed with a constricted opening 43 on top of which rests a flat sheet metal valve 44, similar in construction to the inlet valve. Similarly also, an annular channel 45 is formed around this aperture to limit adhesive effects on the valve. It has been found advantageous not to form the plunger element as one integral piece, but 70 to disassociate the same, the piston head 42 having a limited pivotal connection with the piston rod 46 by means of a pin 47, the upper portion of the piston being formed as a socket to receive the end of the plunger rod. 75 The extreme base of the plunger rod 46 carries an inserted plug 48 which extends below said base and is adapted to contact with the outlet valve and prevent too wide movements thereof. This plug is of narrow 80 dimensions so that there is an annular space thereabout tending to prevent cohesive action 85 between the plate 44 and plug 48.

The piston or plunger rod 46 extends upwardly to a point adjacent the top of the tank 90 and is formed with a series of annular channels or depressions 49 which are adapted to assist in forming a strong connection between the plunger rod and the weighted element 50 thus removing any possibility of axial slip. 95 The weighted element is of lead or any other material of required density and may be cast upon the plunger rod as indicated. Adjacent the top of the weight is an annular member 51 which is adapted to form a bearing 100 surface for a ring 52 fixed to the interior of the casing and which is shaped in the form of a channel with upwardly extending flanges 53 extending circumferentially above the interior of the tank. This ring serves not only 105 as a bearing for the plunger, but also to prevent the movement of liquid from the upper interior to the lower interior of the tank. The necessity of this construction arises from the case where the use of the gasoline, or 110 whatever liquid is used, is insufficient to remove that accumulated by the pump, a surplus being accumulated which would eventually fill the tank to overflowing and create an undesirable pressure. Consequently, it is 115 essential that the action of the pump becomes minimized when the supply of liquid has reached the point sufficient for the requirement of the engine. It is undesirable, however, that the complete closure be made around 120 the plunger for the reason that the air would be trapped in the top of the casing, working against the upward motion of the plunger and thus absorbing considerable energy. In order to obviate this difficulty, there is formed 125 in the ring 52 a valve mechanism 54 which, as is illustrated in Figure II, consists of a bushing 55 having an aperture 56 in its base fitting with a similar aperture 57 in the base 130 of the channelled ring 52. There is formed

also an enlarged space 58 in the upper part of this bushing forming a ledge or shoulder 63 with the lower part of the bushing 55 and adapted to receive a washer element 59 having also an aperture 60 adapted to coincide with the other apertures. Intermediate the washer and the ledge 63 is a valve plate 61 having a formation such as is indicated in Figure III of the drawing. As illustrated in this figure, the valve is formed of sheet metal having four radial projections 62 extending in quadrature around the periphery of the valve, these projections resting upon the shoulder 63 formed on the interior of the bushing or ring. The diameter of the valve is of such a value that when it is moved upwardly the circular portion will completely cover the opening 60, thus effectually preventing the movement of air or of liquid upwardly when a current of liquid is moving through the aperture. On the other hand, the friction of the air current is relatively lower, being insufficient to move the valve upwardly and passing in the annular conduit 64 about the edge of the valve as illustrated in Figure III. When the air is compressed in the upper portion of the casing by the upward movement of the plunger mass 50, the valve 61 resting in its normal position is still further forced downwardly by the action of the air currents, the air, however, passing through the open passages about the valve plate. It is thus apparent that the valve can hardly be affected by the action of a gas and that the movement of a liquid therethrough causes movement of the plate tending to check, or entirely arrest the axial movement of the plunger and thus stopping the pumping action.

The plunger with its attached mass is adapted to be held in a normal position relative to the cylinder from which position it may be moved by the vibration or movement of the casing itself, such as would occur, for example, in an automobile when in motion. Means for holding the plunger element in normal position are incorporated in a coil spring 65 positioned about the cylinder 25 and contacting at one end against the bottom end plate 16, and at its upper end on a shoulder 66 formed adjacent the base of the weighted mass 50, and since the spring is constantly in state of compression through support of the plunger load, any movement of the casing or its support, transmitted to the casing, will tend to cause a relative movement of the plunger and the casing, producing an oscillating or vibratory effect of the plunger in the cylinder, a downward displacement of the plunger being followed by a reverse movement through the action of the spring, these vibrations continuing with rapidly decreasing amplitudes. Because of the length of the coil spring 65, it is apparent that the period of vibration is relatively long and to counteract the effect of an abnormal force applied to the tank, it has been found advantageous to insert an additional spring 76, one end 67 of which is secured to the plunger rod below the mass 50, and the other end 68 mounted free about the top of the cylinder so that for ordinary movement of the plunger, the spring does no work, but merely moves upwardly and downwardly in the tank. However, should the tank be subjected to a severe displacement, the plunger in consequence making an abnormal movement, the free end of the spring in moving down contacts against a ring 69 mounted on the outside of the cylinder which acting in conjunction with the outer spring 65 will rapidly slow down the movement of the plunger and cause an immediate and quick rebound of the same.

The aperture in the top plate or cover is adapted to hold a cylindrical bushing 15 which forms the bearing for a rod 70 slidably mounted therein and adapted to be pushed down by means not shown until the bottom end thereof contacts with the top of the plunger member so that by manual means the plunger may be manipulated to cause the induction of liquid into the tank.

In Figure V and Figure VI are shown modifications of the valve 54, in Figure V there being disclosed a float 100 movable in a cage 101 and carrying a central upwardly extending stem 102 which is adapted to contact with and close the valve 103 when the liquid elevates the float 100. In Figure VI the valve 110 carries upstanding lugs 111 on the upper side thereof to which is pivotally attached the float 112 through the connecting rod 113. The valve casing 114 is divided into two compartments 115 and 116 by the middle valve seat partition 117, which partition has a central aperture which is adapted for closure when the float, lifted by the liquid, draws up the valve plate 110. Free movement through the apertures 118 about the float is provided.

The operation of the plunger and tank mechanism should now be apparent. When applied to an automobile, the uneven roadbed will impart constant vibrations to the attached tank and its contained cylinder which cause relative movements between the piston and cylinder resulting in an irregularly intermittent pumping action. Fuel is thereby raised from the lower main tank and stored in the auxiliary tank at a higher level from which it feeds by gravity to the carburetor. Should the auxiliary tank be empty, the rod 70 is manipulated until sufficient fuel to start the engine is raised, whereupon pump-action is automatically started and the auxiliary tank supplied with fuel until the engine stops or the tank is filled to the ring 52.

Because of the limited pivotal connection

between the piston and piston rod thereby preventing binding combined with the liquid piston seal employed, the efficiency of the pump is materially augmented. Furthermore, by providing means for preventing abnormal displacement of the plunger and for arresting plunger movements when the supply of liquid has reached a maximum amount, the operation of the mechanism is made essentially practical.

The vent 77 provides additional means for disabling the pump should the valve means be insufficient, since with extreme elevation of the plunger by the buoyant force of the liquid or vibration the vent is uncovered and the pressure in the pump chamber brought to normal.

The structure shown in this application is a modification of that shown in the applications of Chester H. Braselton and Fred. B. MacLaren, Serial No. 532,718, and Carl P. Brockway, Serial No. 595,241, in which applications the right to claim certain features of the invention broadly is reserved.

While I have illustrated and described a preferred form of the apparatus, it is of course understood that variations of construction and modifications are permissible within the scope of the claims hereto appended.

What I claim is:

1. In a fuel supply system, the combination of a tank; a pump cylinder within the tank; a weighted plunger adapted to have axial movement in the cylinder; means including a spring for holding said plunger resiliently in a normal position; a ring positioned around the plunger and extending to the inner wall of said tank, adapted to restrain movement of fluid thereabove; and means including a valve adapted to permit the passage of gases only therethrough positioned in said ring.

2. In a fuel supply system, the combination of a tank, a pump discharging into the tank and including a cylinder and a weighted plunger axially movable in said cylinder, means including a spring for resiliently supporting said plunger, and means for arresting the axial movement of said plunger, said

means including a valve and a float for holding the valve in closed position when the sup-

ply of liquid in the tank is sufficient to float the same.

3. In a fuel supply system, the combination of a tank, a pump discharging into said tank and including a pump cylinder, a weighted plunger axially movable in said cylinder, and spring means for resiliently supporting said plunger, and means within said tank including a flutter valve and a float for arresting the axial movement of said plunger.

4. In a fuel feed system, the combination of a tank, a cylinder supported therein, a plunger axially movable in said cylinder, intake and discharge valves cooperating with said cylinder and plunger, a stem pivotally connected with said plunger, a weight carried by said stem, spring means for supporting said weight, and an auxiliary spring surrounding said stem and interposed between the weight and cylinder, said spring being normally inoperative but effective to restrain excessive movements of said plunger.

5. In a fuel feed system, the combination of a tank; a cylinder supported therein; a plunger axially movable in said cylinder; intake and discharge valves cooperating with said cylinder and said plunger; a weight cooperating with said plunger to cause movement thereof due to the inertia of said weight; spring means for supporting said weight; an auxiliary spring interposed between said weight and said cylinder; and a rib integral with said cylinder for supporting said auxiliary spring, said spring being normally inoperative but effective to restrain excessive movements of said plunger.

6. In a device of the class described, the combination of a tank, an inertia-actuated pump discharging into said tank, and including a cylinder and a plunger working therein, float controlled means for rendering said pump inoperative when the liquid in said tank reaches a predetermined level, and means for preventing abnormal displacements of said plunger with respect to said cylinder including a spring free at one end and adapted under abnormal conditions of plunger movement to contact with said cylinder.

In testimony whereof, I affix my signature.
CHESTER H. BRASELTON.
